APPARATUS FOR CONVERTING CONTINUOUS FILAMENTS INTO PRODUCTS CONTAINING STAPLE FIBER

William Ivan Taylor and Leslie Brisbane Gibbins, Spondon, near Derby, England, assignors to Celanese Corporation of America, a corporation of Delaware

Application July 29, 1937, Serial No. 156,297
In Great Britain August 7, 1936

7 Claims. (Cl. 19—1)

This invention relates to apparatus for converting continuous filaments into products containing staple fiber. U. S. Patents Nos. 2,077,078 and 2,077,079 describe the conversion of continuous filaments into products containing staple fiber by causing a bundle of continuous filaments to pass in contact with a cutting surface moving in the same general direction as the filaments but at a different speed therefrom, and 5 pressing the filaments substantially at a point in their length against the cutting surface. The filaments may, as is indicated in U. S. Patent No. 2,077,078, be passed more than once through the cutting device or in a single operation they may 10 be subjected to the action of two or more cutting devices in turn.

The object of the present invention is to provide a simple and convenient means of controlling the pressure rollers in apparatus in which more 20 than one cutting device acts in turn on the bundle of continuous filaments, and in which the pressing rollers are so mounted that their own weight provides the necessary pressure on the filaments against the cutting surfaces. According 25 to the present invention the pressing rollers are mounted in bearings on a lever or levers having pivots displaced some distance horizontally from the nips of the pairs of rollers, and an extension of the lever or one of the levers (or, it 30 may be, a separate lever) is arranged so that it can be gripped or otherwise actuated with one hand of the operative so as to lift the pressing rollers and enable a bundle of filaments to be carried below the pressing rollers so as to be in 35 position for engagement by rollers when the operating lever is released. Preferably the lever mounting of the rollers is so arranged that the pressing roller under which the filaments first pass is lowered into position before the second 40 roller. The pressing roller mounting is conveniently carried on a member carrying the movable roller of a pair of gripping rollers that serve to draw the filaments through the cutting devices. The operating lever is preferably so disposed that 45 it can be actuated by the one hand of the operative used to withdraw the movable gripping roller from the other gripping roller for the insertion of the filaments between the rollers at the start of the operation.

50 The invention may be used in conjunction with apparatus according to U. S. application S. No. 155,200, filed July 23, 1937, corresponding to British application No. 21,96/36, filed August 7, 1936, in which the speed of one cutting surface is 55 less than that of the filaments under treatment,

and the speed of the other cutting surface greater than that of the filaments.

The invention will now be described in greater detail with reference to the accompanying drawing, in which is shown an apparatus wherein the filaments pass through two cutting devices in turn and then through a pair of gripping rollers mounted below the second cutting device.

In the employment of the apparatus shown, the filaments 1 are drawn from a bobbin 2 carried 10 on a shelf 3, and pass over guides 4 and 5, and through a further guide 6 carried on the edge of the shelf 3. From the guide 6 the filaments proceed to a pair of rollers 7, 8, constituting the first cutting device and from the horizontal nip 15 of the rollers 7, 8 they proceed, not now in the form of continuous filaments, since some at least of the filaments have been severed by the first cutting device, under a tension bar 9 and so to a second pair of rollers 10, 11 constituting the 20 second cutting device. The lower, or cutting, roller 7, 10 of each cutting device is a steel roller having sharp edged helical flutes cut in its surface, which, under the pressure applied by the rollers 8, 11, serve to sever the filaments. The 25 upper or pressing roller 8, 11 on each cutting device has a surface in the form of a metal sleeve which may be mounted on a body of sponge rubber. The continuous staple fiber product issuing from the nip of the rollers 10, 11 proceeds 30 vertically downwards through a pair of gripping rollers 12, 13 and thence to the balloon guide 14 of a cap spinning device 15 by means of which the staple fiber product is twisted, and wound as a yarn. The roller 12 is also fluted, the flutes in 35 this case being parallel to the axis of the roller and free from sharp edges, while the roller 13 has a surface of rubber.

The apparatus above described constitutes one 40 of a series of units disposed in a line, in the manner common with spinning machinery. The three rollers 7, 10 and 12 are mounted on three shafts 16, 17, 18 extending the length of the machine and driven at the required speed by means of chains 19 from a gear box 20. The 45 gripping roller 13, engaging with the gripping roller 12, is carried in slotted bearings 21 in a pair of swinging arms 22 (one of which can be seen in the drawing). The arms 22 are suitably loaded, e. g., by means of a weight or spring, as 50 indicated at 33, so that the roller 13 is pressed against the roller 12 so as to grip the filaments firmly. One of the swinging arms 22 has fixed to it a bracket 23 to which a forked lever 24 is pivotally connected at a point 25. The forked

lever 24 is provided at its forked end with slotted bearings 26 in which is carried the pressing roller 8 of the first cutting device. A further forked lever 27 pivotally mounted in bearings 28 between the swinging arms 22 carries in slotted bearings 29 the pressing roller 11 of the second cutting device. The forked lever 27 has a tail 30 which can be pressed or gripped against one of the swinging arms 22 so that the lever 27 is moved 10 and the roller 11 carried thereby is lifted out of contact with the lower roller 10. One arm of the fork of the lever 27 carries a nib 31 engaging beneath the forked lever 24, and when the tail 30 is pressed and the lever 27 is lifted, the nib 15 31 engages and lifts the lever 24 and thereby raises the roller 8 out of contact with the roller 7.

In starting up the device the filaments 1 are drawn from the bobbin 2 over the guides 4 and 5 and through the guide 6. The operator is then 20 able to grip the tail 30 of the lever 27 against the swinging arm 22 whereby the rollers 8 and 11 are lifted from their engaging rollers 7 and 10, and at the same time the arm 22 is swung backwards slightly on its pivot 32 against the force applied 25 at 33 so that the roller 13 is disengaged from the roller 12. The filaments 1 are now led over the roller 7, under the tension bar 9, over the roller 10 and between the rollers 12 and 13. The roller 13 is then allowed to engage with the roller 30 12 and to nip the bundle of filaments which are led through the guide 14 to the cap spinning device 15. When the filaments have been threaded up in this way the tail 30 of the lever 27 is released and the pressing rollers 8 and 11 35 are permitted to engage with the rollers 7 and 10. The depths of the slotted bearings 26, 29 are such that the roller 8 comes into engagement with the roller 7 before the roller 11 comes into engagement with the roller 10. In this way the cutting 40 devices are both brought into operation, and subsequently act to sever the filaments 1 so as to form a staple fiber product which is drawn away from them by the rollers 12, 13 and fed to the cap spinning device 15.

Having described our invention what we desire 45 to secure by Letters Patent is:

1. Apparatus for the production of a continuous staple fiber product from a bundle of continuous filaments, said apparatus comprising a plurality of cutting devices each consisting of a pair of rollers pressed together upon the filaments by the weight of one of the rollers, at least one of said rollers in each pair having a cutting surface, means for drawing a bundle of filaments 50 through said cutting devices in turn, and means for raising together the upper rollers of the cutting devices and for lowering said rollers successively into contact with their lower rollers in the order in which they are reached by the filaments, 55 for the purpose of starting the operation of the apparatus.

2. Apparatus for the production of a continuous staple fiber product from a bundle of continuous filaments, said apparatus comprising two cutting devices each consisting of a pair of rollers pressed together upon the filaments by the weight of one of the rollers, at least one of said rollers in each pair having a cutting surface, a pair of gripping rollers adapted to draw a bundle 60 of filaments through said cutting devices in turn, a pair of swinging levers, bearings in said swinging levers for carrying one of said gripping rollers in gripping contact with the other, a lever having pivots in said swinging levers disposed horizontally 65 from the upper rollers of said cutting de-

vices, bearings in said lever for at least one of said upper rollers, and a handle on said lever adapted to be gripped against one of said swinging levers whereby the upper rollers of the cutting devices may be lifted in the same operation 5 as that in which said swinging levers are swung back to move the gripping roller carried thereby out of contact with the other gripping roller.

3. Apparatus for the production of a continuous staple fiber product from a bundle of continuous filaments, said apparatus comprising two cutting devices each consisting of a pair of rollers pressed together upon the filaments by the weight of one of the rollers, at least one of said rollers in each pair having a cutting surface, means for drawing a bundle of filaments through said cutting devices in turn, means for driving a roller having a cutting surface in one of said cutting devices at a speed less than that of the filaments, means for driving a roller having a cutting surface in the other cutting device at a greater speed than that of the filaments, and means for raising together the upper rollers of the cutting devices for the purpose of starting the operation of the apparatus.

4. Apparatus for the production of a continuous staple fiber product from a bundle of continuous filaments, said apparatus comprising two cutting devices each consisting of a pair of rollers pressed together upon the filaments by the weight of one of the rollers, at least one of said rollers in each pair having a cutting surface, a pair of gripping rollers adapted to draw a bundle of filaments through said cutting devices in turn, a pair of swinging levers, bearings in said swinging levers for carrying one of said gripping rollers in gripping contact with the other, means for driving a roller having a cutting surface in one of said cutting devices at a speed less than that of the filaments and means for driving a roller having a cutting surface in the other cutting device at a greater speed than that of the filaments, a lever having pivots in said swinging levers disposed horizontally from the upper rollers of said cutting devices, bearings in said lever for at least one of said upper rollers, and a handle on said lever adapted to be gripped against one of said swinging levers whereby the upper rollers of the cutting devices may be lifted in the same operation as that in which said 50 swinging levers are swung back to move the gripping roller carried thereby out of contact with the other gripping roller.

5. Apparatus for the production of a continuous staple fiber product from a bundle of continuous filaments, said apparatus comprising two cutting devices each consisting of a pair of rollers pressed together upon the filaments by the weight of one of the rollers, at least one of said rollers in each pair having a cutting surface, means for drawing a bundle of filaments through said cutting devices in turn, a lever for the upper roller of each cutting device, said levers having bearings for said upper rollers, and having pivots horizontally removed from said rollers, and means for swinging said levers together so as to lift said upper rollers for the purpose of starting the operation of the apparatus.

6. Apparatus for the production of a continuous staple fiber product from a bundle of continuous filament, said apparatus comprising two cutting devices each consisting of a pair of rollers pressed together upon the filaments by the weight of one of the rollers, at least one of said rollers in each pair having a cutting surface, a pair of

gripping rollers adapted to draw a bundle of filaments through said cutting devices in turn, a pair of swinging levers, bearings in said swinging levers for carrying one of said gripping rollers in gripping contact with the other, means for driving a roller having a cutting surface in one of said cutting devices at a speed less than that of the filaments and means for driving a roller having a cutting surface in the other cutting device at a greater speed than that of the filaments, a lever for the upper roller of each cutting device, said levers having pivots in said swinging levers horizontally removed from said rollers, connecting means between said levers, and a handle on one of said levers adapted to be gripped against one of said swinging levers whereby the upper rollers of the cutting devices may be lifted in the same operation as that in which said swinging levers are swung back to

move the gripping roller carried thereby out of contact with the other gripping roller.

7. Apparatus for the production of a continuous staple fiber product from a bundle of continuous filaments, said apparatus comprising a plurality of cutting devices each consisting of a pair of rollers pressed together upon the filaments by the weight of one of the rollers, at least one of said rollers in each pair having a cutting surface, means for drawing a bundle of filaments through said cutting devices in turn, means between said cutting devices for tensioning the bundle between said cutting devices, and means for raising together the upper roller of each cutting device for the purpose of starting the operation of the apparatus.

CERTIFICATE OF CORRECTION.

Patent No. 2,140,566.

December 20, 1938.

WILLIAM IVAN TAYLOR, ET AL.

It is hereby certified that error appears in the printed specification of the above numbered patent requiring correction as follows: Page 1, first column, line 53, for the application number "21,96/36" read 21,796/36; page 2, second column, line 71, claim 6, for "filament" read filaments; page 3, second column, line 13, claim 7, strike out the words "between said cutting devices"; and that the said Letters Patent should be read with this correction therein that the same may conform to the record of the case in the Patent Office.

Signed and sealed this 11th day of February, A.D. 1939.

Henry Van Arsdale.
